LEAD HOLDER

Fritz von Allmen, Geneva, Switzerland, assignor
to Fabrique Suisse de Crayons Caran d'Ache
S. A., Geneva, Switzerland, a corporation of
Switzerland

Application July 2, 1941, Serial No. 400,839
In Switzerland February 3, 1941

8 Claims. (Cl. 120—17)

Various types of lead holders are already known with a device for feeding the lead, as a result of pressure applied to a cap. In order to obtain effective clamping of the lead so as to avoid the lead being pushed back into the interior of the body of the lead holder as a result of the pressure exerted on the lead while it is being used, it has been proposed, in particular, to hold it in clamping jaws provided with a conical portion which project from the body of the lead holder through a conical opening provided at the end of the body, these clamping jaws being subjected to the action of a spring which tends to hold their conical surface in contact with the conical surface of the opening. This type of lead holder is provided with a device for feeding the lead formed by a member located in the interior of the lead holder. This member clamps the lead, at the end of the movement of the clamping jaws actuated by the cap, so as to retain it in this position during the return movement of the clamping jaws into their rest position.

Other lead holders have retaining device formed by jaws provided in the interior of the body of the lead holder and serving to clamp the lead during the return movement of the clamping jaws.

All these devices have various defects inherent to their construction. In particular the clamping jaws being very short, the flexibility of their limbs is insufficient and very soon they no longer clamp the lead after they have been released from the seating cone and therefore no longer effect the feed. Consequently the feed of the lead, particularly when it is not calibrated accurately, is irregular and is no longer effected correctly.

Further as the retaining device is provided in the interior of the body it is invisible so that it is not possible for the user to see directly whether the stoppage of the feed of the lead is due to the exhaustion of the reserve of leads or to a defective operation of the lead holder. Finally when the lead engaged in the clamping jaws is short the feed can only take place when the point of the pencil is directed downwards. In fact the feed of the lead, in such a case, is produced by a push by the succeeding lead engaged by the retaining members. But in order that this remains engaged by these members it is necessary that the force of gravity tends to hold it in contact with the preceding lead engaged by the clamping jaws.

The subject of the present invention is a lead

holder by which the above disadvantages are eliminated and which is provided with clamping jaws which emerge from the body of the lead holder and of which the movements are controlled by the cap. It is distinguished from known lead holders by the fact that these clamping jaws are formed by feed members and retaining members.

In the accompanying drawing there is shown diagrammatically a form of construction of a lead holder according to the invention.

Fig. 1 is a longitudinal section on the line I—I of Fig. 7.

Fig. 2 is a longitudinal section on the line II—II of Fig. 7.

Figs. 3 to 5 show various phases of the feed movement, each half of the drawing showing the position at the same instant of a clamping jaw of each group.

Fig. 6 shows a cross section of the jaws on the line VI—VI of Fig. 1, and

Fig. 7 is a cross section of the feed device on the line VII—VII of Fig. 1.

According to Figs. 1 and 2 the lead holder pencil is formed by a body 1, a magazine tube 2 surmounted by a cap 3, a lead guiding tube 4, and clamping jaws, divided into two groups, one group being provided with retaining members 5 and the other with feed members 6.

The body 1 is formed by a polygonal tube of which one end is tapered and is provided with a conical opening 7 forming a seat for the jaws which are rearwardly tapered. The guide tube 4 is rigidly secured to the magazine tube 2, preferably by clinching, and is provided with two pins 8 of which the outer faces a slide along the inner walls b of the body 1. The magazine tube 2 is guided, centered and prevented from rotation in the interior of the body 1 by means of a polygonal projection 9. To the free end of the guide tube 4 there are secured rigidly feed members formed by a group of jaws 6 which emerge from the body 1 through said conical opening 7. The limbs of these jaws are resilient and are formed in such a manner as normally to clamp the lead 11. They are also provided with a conical portion 12 maintained in the clamping position in engagement with the conical opening 7 by a spring 13 which bears against the tapered portion of the tube 1 and acts upon the pins 8 secured to the guide tube 4.

Between the limbs of the feed jaws 6 are located retaining members formed by a group of jaws 5. The inner ends of the limbs of these

jaws 5 are connected together in the interior of the body 1 because they are carried by a tubular body 14 whose inner end frictionally engages and is centred on a boss 10 provided on the guide tube 4. For the purpose of retaining the jaws 5 and 6 angularly relative to the guide tube 4, and to ensure a slideable resilient engagement of the end of the tubular body 14 with the boss 10, the aforesaid inner end is provided with longitudinal slots 15 with which the pins 8 engage. The limbs of the jaws 5 are resilient and are shaped in such a manner that in the released position of the lead the latter can slide between the gripping faces 20 thereof. The limbs of these jaws are provided with a conical portion 17 which is held in the clamping position in the conical opening 7 by the spring 13 which presses against the flange 16 of the tubular body 14.

The feed movement of the lead is produced by exerting a push on the cap and may be divided into four phases:

a. Release of the lead

Assuming that the internal mechanism of the pencil lead holder is in the position shown in Figs. 1 and 2, in which the spring 13 acting on the two sets of jaws tends to cause them to move inwardly into the body 1 and thus causes these to clamp the lead, so as to retain it axially and angularly, then when pressure is applied to the cap 3 the latter pushes the magazine tube 2, the guide tube 4 and the jaws 6, which are secured together, against the action of the spring 13. The jaws 5 partake of this movement as a result of their frictional engagement with the boss 10 through the medium of the tubular body 14. The lead 11 is fed by the feed jaws 6. The movement of the retaining jaws 5 is limited by a shoulder 18 on the tube 14 which comes into engagement with the tapered part of the body 1 (Fig. 3).

b. Feed of the lead

While continuing pushing the cap 3, the movement of the latter effects forward movement of the feed jaws 6 which because of their gripping faces 21, bearing against the lead, feed the latter. During this phase the tube 14 slides on the boss 10 and the retaining jaws 5 rest with their shoulders 18 bearing against the tapered portion of the body 1 and its gripping faces 20 in the open position (Fig. 4). The movement of the cap is limited by the inner edge of the magazine tube 2 coming into contact with the flange 16 of the tube 14.

c. Retention

When the cap 3 is released, the spring 13, acting on the pins 8, tends to cause the feed jaws 6, secured to the guide tube 4, to move rearwardly. The lead partakes of this movement by reason of the action of the limbs of these jaws which press their gripping faces 21 against the lead. The retaining jaws 5 also partake of this movement, as a result of the frictional engagement of the slotted end of the tube 14 with the boss 10, until their conical surfaces 17 come into contact with the conical seating 7 of the opening, which effects the clamping of the gripping faces 20 against the lead 11 so as to retain the latter against the action of the gripping faces 21 of the feed jaws 6 (Fig. 5).

d. Tightening of the jaws

The spring 13, acting on the pins 8, effects the return of the feed jaws 6 into the position shown

in Fig. 1, the gripping faces 21 of these jaws sliding on the lead 11 held by the gripping faces 20 of the jaws of the retaining means 5 when the conical surfaces 17 thereof engage the seat 7. The action of the spring 13 also effects the tightening of the gripping faces 21 of the feed jaws 6 against the lead 11 when their conical faces 12 seat in said conical opening 7. This lead is therefore held in its position by the gripping faces 20 and 21 of the two sets of jaws subjected to the action of the spring 13 and the conical surfaces 12, 17 and 7.

From the foregoing it will be seen that during the whole of the feed movement of the lead 11 this is always clamped by one or other of the sets of jaws in proximity to its end. It thus follows that the feed of the lead is effected normally until the last reserve lead has been used completely. Further the feed of the lead can be effected under all conditions and in all positions of the pencil lead holder, the succeeding lead not playing any part during the various phases of feeding the lead in contact with the separate parts.

The parts of the lead which come into engagement with the feed and retaining members being outside the body 1 and thus visible, the user cannot therefore imagine that there is a defective operation of the lead holder when there solely occurs an exhaustion of the reserve of leads.

By reason of the fact that the clamping jaws projecting from the body are formed by feed and retaining members, it is possible to make these of such a length that no permanent deformation is liable to occur. This great resiliency of the feed and retaining members enables badly calibrated leads to be used, which represents a considerable advantage in comparison with known lead holders.

It is to be observed that a push applied to the end of the lead projecting from the jaws 5 and 6 tends to force the conical surfaces 12, 17 of the latter against the conical surface 7 of the opening which automatically produces a more powerful clamping of the gripping faces 20, 21 against the lead which prevents the latter moving towards the interior of the body 1.

It will be understood that the movement of the cap may be limited either as above described, by the flange 16 coming into engagement with the end of the magazine tube 2, clinched on the guide tube 4, or by the end of the body 1 coming into contact with the bottom of the cap. The free end of the guide tube 4 may be provided with a conical opening 22 or any other known means ensuring that the leads contained in the magazine enter the guide tube 4 one by one.

The slots provided between the limbs of the feed jaws 6 and in which are located the limbs of the retaining jaws 5, are preferably of a width smaller than the leads to be used so that pieces of the leads, broken in the magazine 2 cannot leave the guide tube 4 and for example lodge themselves in the space 23 between the jaws 5 and 6 and thus obstruct the satisfactory operation of these.

It is to be pointed out that the clamping jaws 5 and 6 hold the lead 11 by means of their gripping faces 20 and 21 only. Since these gripping faces have only small surfaces bearing against the lead, a perfect clamping of the latter is thus assured even for non-calibrated leads. The lead not being clamped by means of a knife

edge, there is no danger of it becoming sheared off.

It will be understood that modifications in the details may be made in the form of construction described above by way of example. For example the parts may be secured together in different manner and means for centering the mechanism in the interior of the body may be provided which are different from those described.

I claim:

1. In a lead holder, comprising a tubular body provided with clamping jaws projecting from said body and also provided with a cap for producing the movement of the jaws, the combination of lead feeding means including certain of said clamping jaws and lead retaining means including other of said clamping jaws.

2. A lead holder according to claim 1, wherein said feeding means and said retaining means each include a set of jaws, both sets of jaws projecting from the body of the lead holder, a single seat cooperating with both said sets of jaws, both sets of jaws co-operating with the said seat to clamp the lead in its operative position.

3. A lead holder according to claim 1, comprising a magazine tube to which the clamping jaws of the lead feeding means are connected rigidly, said cap being mounted on said tube, said retaining means being frictionally engaged with said tube.

4. A lead holder according to claim 1, including means for limiting the movement of the retaining means to a fraction of the total movement of said cap and of said feeding means.

5. A lead holder according to claim 1, comprising a guide tube, said retaining means being centred on said guide tube, said feeding means being secured to said guide tube, and means for respectively retaining said feeding means and

said retaining means in their relative angular position.

6. A lead holder according to claim 1, wherein said retaining means is provided with gripping jaws which tend to move away from a lead when in the released position.

7. A lead holder according to claim 1, including a body having a conical seat therein, said clamping jaws of the feeding means and said 10 clamping jaws of the retaining means being provided with conical outer surfaces for cooperation with said conical seat, all of said clamping jaws having inner gripping surfaces for engagement with a lead, and all of said clamping 15 jaws having outer conical faces for engaging with said conical seat, and a spring mounted in said body, said spring normally tending to press the outer conical surfaces of all of said jaws in said conical seat to hold said lead in an operative position.

8. In a lead holder the combination comprising a tubular body having a tapered end, a cap slidably fitted on the other end of said body, a magazine tube secured to said cap and fitting 25 within said body, a guide tube secured to said magazine tube, a flange on said guide tube adjacent said magazine tube, a spring located between said tapered end and said flange, a conical seat in said tapered end, a set of retaining jaws 30 having resilient limbs slidably mounted on said guide tube, a set of feeding jaws having resilient limbs rigidly secured to said guide tube, all of said jaws having conical outer surfaces for co-operation with said conical seating, all of said 35 jaws having internal gripping faces, the limbs of the feed jaws alternating with the limbs of the retaining jaws, and means for limiting the sliding movement of the retaining jaws relatively to the movement of the feed jaws.

FRITZ von ALLMEN.
